GOLF CLUB PUTTER HEAD

Sylvan M. Lubin, 1821 Navaho Circle,
Palm Springs, Calif.

Filed Mar. 29, 1965, Ser. No. 84,474

Term of patent 3½ years

(Cl. D34—5)

FIG.1.

FIG.2.

FIG.3.

FIG.4.

FIG.5.

The broken lines indicating a shaft are for purposes of illustration only.

I claim:

The ornamental design for a golf club putter head, substantially as shown and described.
